RACK FOR PRE-TIED NECKTIES

Bernard A. Penland, Southgate, Mich., assignor to The Ambassador Corporation, Lincoln Park, Mich., a corporation of Michigan

Filed Dec. 6, 1965, Ser. No. 96

Term of patent 7 years

(Cl. D33—8)

FIG. 2

FIG. 1.

FIG. 3.

I claim:

The ornamental design for a rack for pre-tied neckties, substantially as shown.
